DISPLAY COUNTER

Filed March 22, 1928

UNITED STATES PATENT OFFICE

SEVERN G. HONSTEAD, OF NAMPA, IDAHO

DISPLAY COUNTER

Application filed March 22, 1928. Serial No. 263,854.

This invention relates to improvements in display counters.

The object of this invention is to provide a display counter with means for holding a plurality of articles in compartments adjacent display containers, the containers being designed to hold material similar to that in the adjacent compartment, which latter is preferably in receptacles or in prepared packages of predetermined size and design to facilitate handling.

Other features will more clearly herein-after appear by reference to the accompanying drawing and wherein like characters of reference indicate corresponding parts in the drawing, in which:

Fig. 1 is a perspective view;

Fig. 2 is a transverse section; and

Fig. 3 is a longitudinal sectional view through one of the display containers showing the method of supporting the same adjacent the display window.

The present device includes a base A and end walls B. The end walls B include flat central portions b and inclined end sections b'. The flat central portions b of the ends B are connected by means of the central counter C and inclined ends b' are covered and connected by the display windows c. Each display window c supports a display window D which is removably positioned to permit access to the contents of the receptacle d placed thereunder. The receptacle d is supported by hangers E which are fastened by screws e or by other suitable means to the under face of the display framing. It will be noted that the display windows c include a series of spaced glass sections each of which is capable of removal and communicates with a separate container d. The size of these display windows will be determined by the size of the compartments formed thereunder, which latter will be determined by the nature of the goods which is to be accommodated.

The entire arrangement is divided by vertical longitudinal partition F and the space formed by this partition is again divided by horizontal longitudinal partitions f and vertical partitions G. As previously suggested, the arrangement of these partitions can best

be determined according to the use to which the arrangement is to be adapted. Obviously, where the material to be dispensed is of a bulky nature, it will be desirable and necessary to form the various chambers of a larger size and this can be accomplished by omitting portions or entire sections of either the horizontal partitions f or vertical partitions G.

The present invention is contemplated for use in connection with self-service stores and is arranged so that the material contained in the various bins is on display in a sealed glass covered container, readily visible to a prospective purchaser. This provision of the display of the material being dispensed or sold will eliminate to a large degree the necessity of many clerks who would otherwise have their time consumed in supplying the nature of the goods dispensed, including the grade and quality of same, to inquiring customers. By the present arrangement, the prospective purchaser can inspect through the glass windows the same material as is contained in the adjacent bins, and if satisfactory can readily remove the packages in the bins beneath the window which will be properly marked and arranged. By having a series of bins under each window, it will be possible to arrange the same material in packages of varying amounts and these separate packages will be arranged in their prospective bins and properly marked as to price and amount.

While the invention is designed particularly for use in dispensing of groceries, and merchandise of this character, it will also be obvious that same can be readily used in the sale of dry goods, men's furnishings and other finished products of this character.

What I claim as new and useful and desire to secure by Letters Patent of the United States, is:

A display case including a base, vertical end walls and partitions having flat central portions and inclined corner portions, a flat counter extending from the flat central end portions of said end walls and resting upon similar portions of said partitions, inclined display windows arranged between the inclined corners of said ends and being supported upon the inclined portions of said parti-

tions, horizontal partitions arranged between the vertical partitions and forming a series of compartments, and removable carriers positioned beneath said display windows and supported on guideways permitting their lateral movement with relation to said windows.

5 In testimony whereof, I affix my signature.
SEVERN G. HONSTEAD.
